UNITED STATES PATENT OFFICE.

LE ROY FRITZ, OF MENLO, IOWA.

DOOR LATCH.

Application filed October 18, 1927. Serial No. 227,026.

The present invention relates to door latches embodying the use of a latch operating handle arranged at opposite sides of a door and adapted for latch releasing movement upon pulling the respective handle member outwardly away from the adjacent side of the door.

The invention has for an object to provide a latch operating handle of this character which necessitates a pulling movement away from the door thereby preventing accidental release of the latch by the contact of an animal, person or other object coming into engagement therewith.

15 A further object is to provide an apparatus of this character of simple and practical construction, efficient and reliable in performance, which may be easily and quickly arranged in operative position upon the 20 door, relatively inexpensive to manufacture and otherwise well adapted for the purpose for which the same is intended.

Other objects and advantages reside in the special construction and combination of 25 the various elements comprising the invention, reference being had to the accompanying drawings forming a part hereof, wherein:

Figure 1 is a front elevational view of 30 the latch in operative position upon the door,

Figure 2 is a vertical sectional view 35 through the door taken on the line 2—2 of Figure 1,

Figure 3 is a horizontal sectional view taken along a line 3—3 of Figure 1,

Figure 4 is a plan view of the plate forming the pivotal mounting for the latch operating handle, and

40 Figure 5 is a view in elevation of the blank from which the latch keeper is formed.

Referring to the drawing in detail, the invention comprises a double handle member indicated generally at 5 composed of an intermediate section 6 extending diagonally through a slotted opening 7 formed in a door 8 and terminating in handle sections 9 arranged at opposite sides of the door in

50 vertically extending positions and disposed parallel with respect to each other, said handles being maintained in spaced relation from the adjacent face of the door by means of inturned end sections 10. At one side of the door adjacent the opening is arranged a plate 11 having one end thereof indicated at

12 extending at an oblique angle outwardly from the face of the door with its end thereof provided with a vertically extending slotted opening 13. The upper edge of the 60 end 12 of the plate is bent backwardly upon itself to form a bearing for a pin 15 carried by an intermediate section 6 of the handle whereby to form a pivotal mounting for the handle upon the plate. The intermediate section 6 of the handle extending at the opposite side of the door from the plate 11 is provided with an opening 16 through which extends a horizontally disposed latch member 17 having one end pivotally attached to a plate 18 attached to the door, with the opposite end of the latch adapted for engagement with a keeper 19 secured to the door jamb 20.

As shown by Figure 5 of the drawing the 75 latch keeper may be formed from a strip of metal, such as for instance strap iron having an intermediate section 21 formed with a notch 22 along one edge adapted to receive the latch and retain the door in closed position. One end of the blank from which the keeper is formed may be bent at right angles to the intermediate section 21 along the dotted line as shown at 23 to form an attaching base 24 for the keeper. The opposite 80 end of the blank indicated at 25 has its edge corresponding to the edge of the intermediate section 21 formed with the notch 22 substantially cut down and may also be bent along the line as indicated at 26 in a direction toward the base 24 in substantially triangular formation as more clearly illustrated in Figure 3. The end 25 thus cooperates with the intermediate section 21 to prevent the bending of the keeper inwardly 85 should an object accidentally strike against the same.

An ear 27 is formed on the inner face of the plate 11 and disposed within the slotted opening 7 of the door to which is attached one end of a spring 28 connecting the intermediate section 6 of the handle whereby to normally retain each end of the handle inwardly against the respective sides of the door.

In the operation of the device it will be apparent that the latch 17 may be raised in engagement with the keeper moving either handle member 9 outwardly away from the door. The spring 28, upon release of the handle, will return the handle into its normal position as indicated in

Figure 2 so that upon the closing of the door the latch will properly engage the keeper and retain the door in closed position.

5 It is obvious that the invention is susceptible of various changes and modifications, without departing from the spirit or scope of the invention or sacrificing any of its advantages, and I accordingly claim all such 10 forms of the device to which I am entitled.

Having thus described my invention, what I claim as new is:

15 In a device of the class described, a latch operating member comprising a double ended handle including an intermediate section extending diagonally through an opening formed in a door and terminating at opposite sides thereof in handle members extending in parallel relation to each other,

said handle members having their ends extending inwardly in abutting relation with the door whereby to retain said handle outwardly from the adjacent sides of the door, a plate attached at the one side of the door having its upper end formed with a slotted opening for receiving the intermediate section of the handle, means for pivotally mounting the handle at the upper edge of said plate, a latch arranged at the opposite side of the door and connected with the handle for operation thereby, a keeper engageable with one end of the latch and a spring yieldably connecting the handle with the plate whereby to normally retain the opposite end of the handle against the respective sides of the door.

20 25 30 35 In testimony whereof I affix my signature.

LE ROY FRITZ.
